UNITED STATES PATENT OFFICE.

DAVID GESSNER, OF WORCESTER, MASSACHUSETTS.

PROCESS OF TREATING CLOTH.

SPECIFICATION forming part of Letters Patent No. 782,845, dated February 21, 1905.

Application filed August 23, 1904. Serial No. 221,835.

To all whom it may concern:

Be it known that I, DAVID GESSNER, a citizen of the United States, and a resident of Worcester, county of Worcester, and State of 5 Massachusetts, have invented a new and useful Improvement in Processes of Treating Cloth, of which the following is a specification.

The object of my present invention is to provide means whereby cloth may be given the 10 qualities which have heretofore been given to it by hand operations, such as plate-pressing and sponging, to provide the cloth with a finish which is largely free from liability to being spotted by water or shrinking.

15 The apron or aprons that I employ in carrying out this invention are preferably applied to a machine which is substantially like that described in my Letters Patent No. 565,072, dated August 4, 1896, to which reference is hereby made, and which machine is shown in the accompanying drawings to the extent that it is necessary for a disclosure of this invention taken in connection with the description of said patent.

20 In the accompanying drawings, Figure 1 is an end view of the machine. Figs. 2 and 3 are end views of sufficient of the machine to show two modifications of the form shown in Fig. 1.

25 1 is the end frame, fastened to one end of the base-plate 2.

30 3 is the main or pressing cylinder, which is internally heated by steam.

35 4 is the bed or press plate, which is internally heated and which can be moved vertically up and down, being guided in this direction by forked guides 5.

40 At 6 the bed-plate is shackled to link 7, which has a screw-threaded connection 8 to unite it with the shackle 9, which at 10 is pivotally connected to carriage 11, that moves in guides 12 of the frame 1, so that when the cam-shaft 13 is turned so as to bring the cam 14 into the position shown in the drawings it will 45 force (through pillow-block 15) the carriage 11 upward, bringing the bed-plate 4 into pressing position.

The manner in which the shaft 13 is operated need not be reiterated here, as it has been fully

described in my Patent No. 565,071, dated 50 August 4, 1896, which was pending at the same time as my Patent No. 565,072 above referred to.

16 is a dry endless felt apron passing between the cylinder 3 and the bed-plate 4 over 55 the cylinder 17, which is driven in the direction of the arrow from the main cylinder 3, as shown in my said Patent No. 565,071.

18 is a swivel-roller on the outside of the apron, which by its swivel acts as an automatic 60 regulator to insure the straight run of the apron 16. 19 is another roller mounted upon a carriage 20, which slides upon ways 21 on a bracket 22 and is operated by a hand-wheel 23, so as to serve as a take-up for the slack of 65 the apron.

24 25 are apron guide-rolls.

26 is a coil of steam-pipes whereby the apron 16 is maintained dry.

27 is a non-endless moist cotton apron, 70 which in Fig. 1 extends from the supply-roll 28 under and over the guide-rolls 29 and 25 between the endless apron 16 and the cylinder 3 to the lap-roll 30. In Fig. 2 it extends to the lap-roll 30. In Fig. 3 it extends from the 75 lap-roll 28^a to the lap-roll 30 without passing between the bed and cylinder as in the other figures. The supply-roll of the apron 27 is wet before it is placed in the machine.

31 is the cloth, which is guided by the rolls 80 32 and 33 past the brush 34 to the roll 25, whence in Fig. 1 it enters between the heated cylinder 3 and the moist apron 27 and is wound up therewith upon the lap-roll 30. In Fig. 2 85 the cloth pursues the same course, excepting that it is wound up separately from the wet apron 27. In Fig. 3 the cloth pursues the same course and is wound up with the apron 27, which, however, it does not join until af- 90

ter it has been pressed on the heated cylinder 3.

In all of the figures the cloth is shown as being next to the surface of the cylinder 3, the apron or aprons being between it and the press-plate. Although for many kinds of 95 cloth I prefer this arrangement, I do not wish to be limited thereto, because the position of the cloth and wet apron may be reversed,

bringing the wet apron next the surface of the cylinder 3. Where the moist apron does not come between the cloth and the bed-plate and the cloth is of such a texture as to stand 5 the friction against the bed-plate, the felt apron 16 may be dispensed with. For example, in the construction shown in Fig. 3 with certain kinds of cloth the apron 16 might be omitted.

10 Having thus described my invention, I claim as new and desire to secure by Letters Patent—

1. The process of treating cloth which consists in subjecting the same to a hot pressing in contact with a moistened apron, and wind-

ing the same up with said apron while still 15 retaining the pressing heat.

2. The process of treating cloth which consists in subjecting the same to a hot pressing and winding the same up with a moistened apron while still retaining the pressing heat. 20

In testimony whereof I have signed my name to this specification in the presence of two subscribing witnesses.

DAVID GEESNER.
